INSULATING COVERING

Robert F. Massa, New York, N. Y.

Application April 11, 1941, Serial No. 388,004

6 Claims. (Cl. 154—44)

This invention relates to insulating coverings of the character used for the comfort and protection of man, and in particular coverings made of layers of matted, or felted, fibrous materials.

Paper in the form of thin sheets is now available which is substantially pure fibre and contains a minimum of loading materials. This paper, especially that sold for personal purposes, such as the so-called toilet tissues and facial tissues, is comparable to a loose felt and has excellent insulating qualities. It has, however, so little strength and other wearing qualities that even for its ordinary intended uses it is not unusual to sell it as double or triple-ply.

It has been proposed to employ this tissue type of paper in the form of superimposed sheets as the material for coverings such as blankets, comforters and the like, because of its low cost and excellent insulating properties. The proposals have had little success because of the weakness and poor wearing qualities of the paper. Recently some success has been attained by enclosing the superimposed sheets in a casing of comparatively strong woven material. The casing while it provides the necessary strength and resistance to wear raises the cost to such a point that the paper article has little if any price advantage.

I have found that satisfactory insulating coverings can be made without the use of the fabric coverings.

It is an object of this invention to provide a novel insulating covering, such as a blanket, comforter, and the like, made of a plurality of superimposed sheets of thin, porous, felt-like fibrous material which can be easily and cheaply manufactured and which has sufficient strength and wear resistance for a long life in the intended use.

It is also an object of this invention to provide a novel insulating covering, such as a blanket, comforter, and the like, made of a plurality of superimposed sheets of thin, porous, felt-like paper which is very flexible and strong and is free from paper rattle; the novel covering furthermore having a high insulating value and being very light as compared to its insulating value.

It is a further object of the invention to provide a novel insulating covering such as a blanket, comforter, and the like, made of a plurality of sheets of thin, porous, felt-like fibrous material provided with reinforcing strands between the superimposed sheets and attached thereto, the reinforcing strands being arranged

in at least two major directions and being of somewhat shorter overall length than the sheets whereby stresses applied to the insulating covering are applied substantially only to the strands and the tendency to tear or wear the sheets in service is reduced to a minimum; the reinforcing strands, furthermore, space the sheets between which they occur and thus provide insulating air spaces, the strands because of their lesser overall length cause the sheets to form small wrinkles or waves when no stresses are applied and thus further provide insulating air spaces.

It is a still further object of the invention to provide a novel insulating covering such as a blanket, comforter, and the like, made of a plurality of sheets of thin, porous, felt-like fibrous material provided with reinforcing and spacing strands between the superimposed sheets and attached thereto, the reinforcing strands being attached to the sheets by an adhesive applied to the strands before the strands are positioned between the sheets thus spacing the sheets apart by the thickness of the strands and at the same time preventing the closing of the pores of the paper except at the lines of contact with the strands.

The further objects and advantages of the invention will be better appreciated from the following description of a present preferred embodiment of the invention and a present preferred mode of manufacturing it, taken with the accompanying drawings, in which

Fig. 1 is an isometric view with parts broken away showing the construction of the novel covering of my invention,

Fig. 2 is an enlarged fragmentary sectional view taken on line 2—2 of Fig. 1,

Figs. 3, 4 and 5 are diagrammatic views illustrating the steps employed in manufacturing the novel insulating covering.

The novel insulating covering of the invention will, for the purposes of the disclosure, be described as the blanket or comforter 10 of Figs. 1 and 2. It is to be understood, however, that the novel article is not limited to such form and use and if desired may be produced in any size and shape and may be used for industrial as well as domestic purposes.

Blanket 10 is made up of a plurality of layers or sheets 11 of thin, porous, felt-like fibrous material. A cheap and convenient material at present preferred for sheets 11 is the paper now available and known as facial tissue, some of the high grade toilet tissues are also suitable.

The tissue papers preferred are those that are very thin and are made substantially entirely out of paper, or cellulose, fibre with a minimum of loading or sizing material. The preferred tissues are of loose and porous structure. Often these are creped, or have an undulating cross-section. The preferred tissues resemble a loose felt and are of excellent insulating quality.

The number of sheets 11 employed may vary widely and in any case will depend on the results desired. A blanket 10 with twelve sheets 11 has been shown. Such a blanket is comparable in insulating value to the better grade blankets made of the usual materials. As just stated a larger or smaller number of sheets 11 may be used as the service conditions warrant. Sheets 11 are reenforced by reenforcing material that is interposed between and united to them. The reenforcing material may be in the form of strands 12 or in the form of loose netting, or webbing, 13, or some of the reenforcing material layers may be in the form of strands 12 and others in the form of netting, or webbing, 13. In any case, the reenforcing material layers may be interposed between pairs of sheets 11 or two or more sheets 11 may separate the reenforcing layers.

The reenforcing material is united to sheets 11 by an adhesive. Various mucilages, glues and cements are suitable for the purpose. At present, rubber latex is preferred as this material when dry is substantially odorless and readily flexible. Enough of the adhesive is used to at least unite each reenforcing layer 12 or 13 with the sheets 11 in contact with it. The adhesive is applied to the reenforcing material before the reenforcing material is positioned between the sheets so that the pores of the sheets are not closed by the adhesive except along the line of union. The adhesive should preferably contain at least one ingredient that wets the sheets so that when these dry they will assume, at least adjacent to the line of union, a wavy surface. Thus, further insulating air spaces are provided between the sheets. It is, of course, evident that the reenforcing material by spacing the sheets also provides insulating air spaces.

Reenforcing layers 12 and 13 are somewhat less in overall length than the corresponding overall dimensions of the sheets 11. By reason of this whenever any pull is exerted on blanket 10 the strain is taken up by the reenforcing layers 12 and 13 and sheets 11 are not stressed. This difference in overall length between the reenforcing layers and sheets 11 causes further waves or undulations in sheets 11 when no stresses are applied. This further increases the insulating air spaces.

The reenforcing layers extend to the very edges of the blanket 10. The edges of the blanket 10 are closed by cementing the edges of sheets 11 together with adhesive, preferably the adhesive is applied along a band spaced from the edges of sheets 11, as the band between lines a—a and b—b of Fig. 2. The area to which adhesive is applied is preferably covered by a tape 14, which may be strong paper or woven material. Again rubber latex is preferred as the adhesive. When the edges of sheets 11 are cemented together and tape 14 is applied in one operation, enough adhesive is preferably employed to unite tape 14 to all of sheets 11. Tape 14 is preferably of such a width that its inner edge portion extends inwardly of the cemented band and is not

attached to sheets 11. Where the tape is omitted the sealed edge of the blanket 10 may have coloring material applied thereto to produce a colored border.

Reenforcing layers 12 are made up of a plurality of closely spaced, substantially parallel strands of yarn, thread, or other such material. The strands of one, or more, of layers 12 are run in one direction while those in another layer, 10 or layers, are run at an angle to said one direction. It is highly desirable that the spacing of the strands, at least in the outer layers, be close enough so that when the blanket is grasped the fingers must overlay reenforcing strands. A spacing of $\frac{1}{8}$ " to $\frac{1}{2}$ " between strands has been found satisfactory although smaller or greater spacings may be used. The strands may be farther apart in the inner layers than in the outer layers, and in some cases inner layers may be entirely omitted. When inner layers of the reenforcing material are eliminated it is generally preferred to unite the unreenforced sheets 11 together as by spots or lines 25 of adhesive. When layers 13 are employed the same spacing of the strands of the netting or webbing must be observed. Also with this material the mesh must be large enough to prevent the adhesive from bridging over the meshes.

In making blanket 10 with reenforcing layers 12, I mount two rolls 15 as shown in Fig. 3. On each of these rolls is tissue sheet 11 in extended length as it comes from the mill. This tissue may be either single or multi-ply. The tissue may be, say, seven feet wide. The tissue from rolls 15 is led to roll 16 and wound thereon. Simultaneously are also wound on roll 16 and between the tissues a plurality of substantially parallel strands 12, spaced as hereinabove set forth. Strands 12 prior to reaching roll 16 pass over roll 11 from spools 18. Roll 17 dips into a bath 19 of cementing material such as a rubber latex so that strands 12 are impregnated to the desired degree with the cementing material in passing over roll 17. The viscosity of the cement and the size and quality of the strand material can be adjusted to give the desired penetration. Thus, the strands may be coated with adhesive so that they will be united to one sheet 11 on each side of them, or to two or more sheets 11 on each side of them. Sufficient tension is maintained on strands 12 during the winding operation so that the overall length of the strands 12 will be somewhat less than the overall length of sheets 11. When the rolling is finished the multi-ply material thus formed is cut into, say, seven foot sections 20. These sections 20 may now be piled in a pile 21 preparatory to the next step.

The next step in the manufacture is shown in Fig. 4 in which the sections 20 are taken from the pile 21 by hand, or by automatic devices, not shown, and laid one after the other close together, or slightly overlapping each other, onto strands 12 as they pass from contact with adhesive applying roll 17 to the roll 22 onto which tissue from roll 23, and the sections 20 are also rolled. The sections 20 are rotated in laying them on the strands 12 so that the strands already present in these sections lie at right angles with the strands 12 upon which the sections are being placed. The strands 12, having been impregnated with adhesive, will adhere to the tissue from the roll 23 and to sections 20. If the tissue on rolls 15 and 23 is two-ply, we now have six layers of tissue on roll 22 with two layers of strands 12, one layer lengthwise and one across the sheets.

Two rolls 22 having been made, a twelve layer blanket may now be formed by placing the rolls 22 as shown in Fig. 5 and winding their contents onto roll 24. The material from the two rolls 22 is joined together by running a set of strands 12 between the material from the two rolls just as was done in the step illustrated in Fig. 3. An alternative way of connecting the material from rolls 22 is by applying an adhesive to the surfaces that are to be brought together, applying it in lines or in spots shown at 25 in Fig. 1. This may be done automatically or by hand.

Blankets of greater thickness may be made either by uniting the material from three rolls 22 in one or the other of the ways just described or by adding single or multiple sheets 11 between two or more layers of material from rolls like rolls 22 and securing them in place by one of the methods already described.

When the rolling is completed the roll is removed and the material cut into seven foot lengths to form a blanket 10 seven feet by seven feet. These blankets then have the edges sealed and binding tape 14 applied to complete them.

The edges may be sealed automatically or by hand. Latex, or other adhesive, thinned to a point where it will penetrate the sheets 11 is applied in a band at or adjacent the edges of blanket 10 and allowed to dry under sufficient pressure to insure that sheets 11 lie close together. The tape 14, if used, may be applied at the same time or later. Tape 14 is of sufficient width so that there shall be no bond between the tape and unreinforced paper.

If tape 14 is not used the edges of blanket 10 may be colored to provide a colored border. When reinforcing material 13 is employed a blanket may be formed in one operation as the rotation to obtain the angular spacing of the reinforcing strands is not necessary.

I claim:

1. A heat insulator of the kind described and having fine interstices to permit the passage of air therethrough, which heat insulator comprises in combination a plurality of superimposed layers, each layer consisting of at least one sheet of unwoven, porous, felt-like fibrous material of tissue-like thinness, and spaced narrow, flexible stranded reinforcement extending in one direction, positioned between certain of said layers and attached thereto and spacing the layers, and additional, spaced, narrow, flexible, stranded reinforcement extending in a direction at an angle to the direction of said first mentioned stranded reinforcement and positioned between other of said layers.

2. A heat insulator of the kind described having fine interstices for the passage of air therethrough, which heat insulator comprises in combination a plurality of superimposed layers, each layer consisting of at least one sheet of unwoven, porous, felt-like, fibrous material of tissue-like thinness having a normally retracted length and an extended length, the thickness in the retracted length being greater than in the extended length, and spaced, narrow, flexible stranded reinforcement extending in one direction positioned between certain of said layers and attached thereto and spacing the layers, and ad-

ditional flexible, spaced narrow, stranded reinforcement extending in a direction at an angle to the direction of said first mentioned stranded reinforcement.

3. A heat insulator of the kind described having fine interstices for the passage of air therethrough, which heat insulator comprises in combination a plurality of superimposed layers, each layer consisting of at least one sheet of unwoven, porous, felt-like, fibrous, creped material of tissue-like thinness, and spaced, narrow, flexible, stranded reinforcement extending in one direction and positioned between certain of said layers, attached thereto and spacing the layers, and additional, spaced, narrow, flexible, stranded reinforcement extending in a direction at an angle to the direction of said first mentioned stranded reinforcement positioned between certain other layers.

4. A heat insulator of the kind described having fine interstices for the passage of air therethrough, which heat insulator comprises in combination a plurality of superimposed layers, each layer consisting of at least one sheet of unwoven, porous, felt-like, fibrous material of tissue-like thinness having a normally retracted length and an extended length and spaced, narrow, flexible, stranded reinforcement of a length not greater than the normal retracted length of the sheets positioned between certain of said layers and attached thereto.

5. A heat insulator of the kind described having fine interstices for the passage of air therethrough, which heat insulator comprises in combination a plurality of superimposed layers, each layer consisting of at least one sheet of unwoven, porous, felt-like, fibrous material of tissue-like thinness having a normally retracted length and an extended length with greater thickness in the retracted than in the extended length, and spaced, narrow, flexible, stranded reinforcement of a length not greater than the normal retracted length of the sheets extending in one direction positioned between certain of said layers, attached thereto and spacing the layers, and additional, like stranded reinforcement extending in a direction at an angle to the direction of said first mentioned stranded reinforcement and positioned between certain other of said layers.

6. A heat insulator of the kind described having fine interstices for the passage of air therethrough, which heat insulator comprises in combination a plurality of superimposed layers, each layer consisting of at least one sheet of unwoven, porous, felt-like, fibrous, creped material of tissue-like thinness, and spaced, narrow, flexible, stranded reinforcement extending in one direction and positioned between certain of said layers, attached thereto and spacing the layers, and additional, spaced, narrow, flexible, stranded reinforcement extending in a direction at an angle to the direction of said first mentioned stranded reinforcement positioned between certain other layers, the strands of said stranded reinforcement and the strands of said additional stranded reinforcement being so spaced that when said heat insulator is grasped by the hand the fingers always overlay stranded reinforcement.

ROBERT F. MASSA.
